H. ETHERIDGE

POLE

Filed August 13, 1924

Patented May 18, 1926.

UNITED STATES PATENT OFFICE.

HARRY ETHERIDGE, OF ZELIENOPLE, PENNSYLVANIA.

POLE.

Application filed August 13, 1924. Serial No. 731,750.

My invention relates to the improvement of wooden poles, such as are now in common use for the support of overhead wires, electrical conductors, lights and the like.

5 In the present practice the wooden butts of such poles are inserted in holes in the ground, and the useful life of such poles is generally measured by the time required for the rotting off of the subterranean portion 10 of the pole. Then the pole must be removed and a sound pole substituted. Where the removed pole is a long one, its rotted butt may be sawed off and the pole reused where a less elevation of the supported structure is 15 required, but replacement because of rotting is a very large item of expense to public service corporations. Furthermore, such rotting frequently remains unnoticed until an accident occurs.

20 In some cases the holes have been enlarged and sleeves of concrete cast about the butts of the poles, but even this does not cure the tendency to rot but simply delays the inevitable deterioration of the poles, for the 25 wood enclosed within the sleeves and protruding below the same will continue to rot.

The object which I have in view is the entire elimination of the danger of rotting, and I accomplish this purpose by the use of a 30 composite pole having an aerial portion of wood and a butt of reinforced concrete, which latter is inserted in the ground. The wooden portion of the pole is preferably detachably connected to the reinforced concrete butt, so that the latter may be made in 35 quantities and preferably in several sizes and attached as needed to the wooden poles when poles are to be erected.

I have also invented a new and improved 40 reinforced concrete butt for wooden poles, which may be readily attached to and detached from the latter and which will function with the wooden or aerial portion of the pole to provide an integral pole structure of 45 great strength and longevity of service.

The juncture between the concrete butt and the wooden aerial portion of the combination pole is preferably above the ground when the pole is erected, thus raising the 50 wood above attack by dampness, and the protruding top of the butt is preferably provided with a metallic protection or armor to prevent injury to the concrete by impact, as by vehicle wheels striking the butt.

55 I have also invented a new and improved metal reinforcement for the concrete butt.

Other novel features of construction, and also of arrangement of parts will appear from the following description.

In the accompanying drawings, which are 60 however not intended to limit the scope of my present invention but simply to illustrate the best embodiment of its principles at present known to me, Fig. 1 is a broken elevation showing one of my composite poles; Fig. 2 is an enlarged plan view of the reinforced butt with the wooden pole removed; Fig. 3 is an elevation of the metallic members of the butt as they appear before the concrete is poured; Fig. 4 is a broken 65 70 75 view similar to Fig. 3; and Fig. 5 is a perspective view of the pole and butt assembled.

The following is a detailed description of the drawings.

Referring first to Fig. 1, A represents the 75 wooden upper or aerial portion of the combination pole and B its reinforced concrete butt. The butt is embedded in the ground for a sufficient distance to give the proper anchorage to the combination pole and preferably protrudes therefrom for six or eight inches. Thus I have roughly indicated the ground level by the dotted line a—a in Fig. 1. The upper end of the butt is armoured and protected by a circumferentially disposed metal collar C which protects the top 80 of the butt against spawling and other disintegration which might result from impacts, such as from vehicle wheels. The top 1 of the butt is flat and is flush with the top 85 of the collar C. The collar is anchored in place to the concrete by the chord-like metal struts 2 which have their ends welded or riveted in holes in the collar and which are sufficiently below the top of the collar to be 90 materially embedded in the concrete.

The lower end of the wooden pole A rests on the top 1 of the butt B, and the pole A is attached to the butt in such a manner that the butt may be readily secured to 100 the wooden pole or be detached therefrom.

Thus I prefer to use a pair of flat metal bars D whose lower ends are permanently embedded in the concrete of the butt B, and which extend vertically from the top 1 of said butt, being disposed approximately 105 ninety degrees apart relative to the axis of the butt and in planes which form substantially a right angle with each other.

The butt is adjusted to the wooden pole, substantially as shown in Fig. 1 and bolts 3 are inserted through holes 4 in the bars 110

D and through holes 5 bored through the wooden pole, and nuts and washers are placed on the ends of the bolts which protrude from the pole A. The nuts are then 5 tightened and the pole A and butt B are thus united together, and the composite pole is ready for erection. The holes 5 are oppositely inclined so that the adjacent bolts 3 will not interfere.

10 It is evident that the two bars D, being disposed at right angles to each other define an angle-shape whose sides are mechanically completed when the pole is bolted in place. This shape is recognized 15 as the strongest and stiffest of structural shapes. As the greatest widths of the bars are opposed at right angles to each other, each bar successfully assumes and resists the strains which the other bar is less able 20 to resist.

The butt B is of concrete reinforced by metal, and is shown as of the following preferred construction. In its metallic skeleton, E represents a plurality of metal 25 anchors which are disposed longitudinally of the butt and which are first fixed in proper position relative to each other by means of suitable metallic connections. Thus I may use for this purpose metal annuli F to which the anchors are spot welded, riveted or otherwise suitably attached. Thus in Figs. 1 and 3 I show one of said 30 annuli adjacent to either end of the anchors, thus holding the same in proper spaced relation to each other. I have shown the skeleton in this form as tapering toward its lower end, thus providing for a downwardly tapering butt, but if desired the skeleton may be 35 of constant diameter, thus providing for a 40 cylindrical butt.

In Fig. 2 I indicate by the cylindraceous, dotted lines b and b' different diameters of wooden pole mounted on the same size of butt, the use of the two bars D and the 45 positioning thereof at about ninety degrees apart permitting a relatively large range of pole sizes to be accommodated with one size of butt. This enables me to standardize the butts in a small number, say two or three 50 sizes, which will between them fit the usual ranges of diameters in wooden poles which are obtainable.

It is evident that my improved reinforced 55 concrete pole butt is not susceptible to rotting and is practically indestructible. The attachment of the wooden or aerial portion of the pole to the butt is such that they are united into a composite structure with all the strength of the conventional wooden pole. In case a pole breaks or is otherwise 60 rendered unserviceable, it may be detached from its butt and a new pole substituted.

It is apparent that my invention will 65 accomplish a great advance in pole usage, since the life of a wooden pole will be greatly

prolonged and its reliability much increased. My improved reinforced concrete butt is inexpensive in the material required, and the time and labor necessary for its manufacture are relatively small.

70

What I desire to claim is:—

1. In a composite pole for the purposes described, the combination with a wooden pole which forms the aerial portion of the structure, of a concrete butt adapted to be 75 embedded in the ground and upon which the wooden pole is mounted, and a pair of metal bars having their lower ends embedded in the concrete and extending upwardly from the butt, said bars being disposed in vertical planes at substantially right angles to each other, the butt end of the wooden pole occupying the angle defined by the bars and being attached thereto, the 80 two bars providing the anchorage of the 85 wooden pole to the butt.

2. In a composite pole for the purpose described, the combination with a wooden pole which forms the aerial portion of the structure, of a concrete butt adapted to be 90 embedded in the ground and upon which the wooden pole is mounted, and a pair of flat metal bars having their lower ends embedded in the concrete and extending upwardly from the butt, said bars being disposed with their greater widths in vertical planes at substantially right angles to each other, the butt end of the wooden pole occupying the angle defined by the bars and being attached thereto, the two bars providing 95 the anchorage of the wooden pole to the 100 butt.

3. In a composite pole for the purposes described, the combination with a wooden pole which forms the aerial portion of the structure, of a concrete butt adapted to be 105 embedded in the ground and upon which the wooden pole is mounted, a pair of metal bars having their lower ends embedded in the concrete and extending upwardly from the butt, said bars being disposed in vertical planes at substantially right angles to each other, the butt end of the wooden pole occupying the angle defined by the bars, the two bars providing the anchorage of the 110 wooden pole to the butt, and stay-bolts connecting said wooden pole to said bars, said stay bolts being disposed at right angles to each other.

4. In a composite pole for the purposes described, the combination with a wooden pole which forms the aerial portion of the structure of a concrete butt adapted to be 115 embedded in the ground and upon which the wooden pole is mounted, a pair of flat metal bars having their lower ends embedded in the concrete and extending upwardly from the butt, said bars being disposed with their greater widths in vertical planes at substantially right angles to each 120

other, the butt end of the wooden pole occupying the angle defined by the bars, the two bars providing the anchorage of the wooden pole to the butt, and stay-bolts connecting said wooden pole to said bars, said stay bolts being disposed at right angles to each other.

5. A concrete pole butt having protruding from its top a pair of metal pole anchoring bars, said bars being disposed in planes at substantially right angles to each other so as to define the angle which is to be oc-

cupied by the pole, and said bars forming the means for connecting the pole to the butt.

15 6. A concrete pole butt having protruding from its upper end a pair of flat metal pole anchoring bars, the greater widths of said bars being disposed in planes substantially at right angles to each other, and said bars forming the means for connecting the butt to the pole and the pole occupying the angle defined by the bars.

20 HARRY ETHERIDGE.
